HEAD UNIT FOR A CARPET SWEEPER

Robert L. Colver, Sunnyvale, Calif., assignor to H. Goldschmidt and Associates, Inc., Menlo Park, Calif., a corporation of California

Filed July 11, 1960, Ser. No. 61,301

Term of patent 14 years

(Cl. D9—2)

F i g. 1

F i g. 2

FIGURE 1 is a perspective view taken from the top and front of a head unit for a carpet sweeper, showing my new design; and

FIGURE 2 is a perspective view taken from the top and side thereof.

I claim:

The ornamental design for a head unit for a carpet sweeper, as shown.
